(57) CLAIM

The ornamental design for a bracelet, as shown and described.

DESCRIPTION

FIG. 1 is a top view of a bracelet showing my new design, it being understood that the links continue for an indeterminate length;

FIG. 2 is a top plan view of a single link thereof;

FIG. 3 is a rear elevational view thereof;

FIG. 4 is a right side elevational view thereof;

FIG. 5 is a front elevational view thereof;

FIG. 6 is a left side elevational view thereof;

FIG. 7 is a bottom plan view thereof; and,

FIG. 8 is a perspective taken from the front, top and right sides thereof.
